UNITED STATES PATENT OFFICE.

NATHAN B. DENISON, OF PAWTUCKET, RHODE ISLAND, ASSIGNOR TO PEERLESS BAKING EQUIPMENT COMPANY, OF BOSTON, MASSACHUSETTS, A CORPORATION OF MASSACHUSETTS.

GAS BURNER.

1,412,044.

Specification of Letters Patent. Patented Apr. 11, 1922.

Application filed March 12, 1920. Serial No. 365,300.

To all whom it may concern:

Be it known that I, NATHAN B. DENISON, a citizen of the United States, residing at Pawtucket, in the county of Providence and 5 State of Rhode Island, have invented certain Improvements in Gas Burners, of which the following description, in connection with the accompanying drawings, is a specification, like reference characters on the drawings indicating like parts in the several figures.

This invention relates to gas burning apparatus and is concerned particularly with apparatus of this character used for heating ovens and the like.

15 The invention aims to devise an apparatus of this character which can be economically manufactured, in which a very complete combustion of the gas can be obtained, which shall be convenient to control, and 20 with which the danger of explosions will be eliminated. The nature of the invention will be readily understood from the following description when read in connection with the accompanying drawings, and the 25 novel features will be particularly pointed out in the appended claims.

Referring now to the drawings,

Figure 1 is an end elevation of an oven equipped with a burner mechanism constructed in accordance with the present invention;

Fig. 2 is a side elevation of the parts of the burner mechanism with which we are more particularly concerned here;

35 Fig. 3 is a plan view of the mechanism shown in Fig. 2;

Fig. 4 is a cross sectional view of the valve for the main burner;

Fig. 5 is a side elevation of the pilot 40 burner;

Fig. 6 is a plan view of the control handle and the parts immediately associated therewith;

Fig. 7 is a front elevation of the parts 45 shown in Fig. 6;

Fig. 8 is a cross sectional view of the main burner;

Fig. 9 is a plan view partly in cross section of the pilot burner valve and the operating 50 means therefor; and

Fig. 10 is a plan view of a modified construction.

The construction shown comprises an oven 2, Fig. 1, of a horizontal cylindrical type 55 widely used in bakeries. The main burner

3, Figs. 2 and 3, extends longitudinally of the oven 2 immediately below it, the bottom of the oven being cut away, as indicated at 4, Fig. 3, immediately over the burner. This burner is connected by a pipe 5 to a mixing 60 valve 6 of any suitable construction, herein shown as the well known Hale gas mixer. This mixer includes a valve 7 provided with a plug 8 having a slot therethrough and mounted to rotate in the valve casing. A 65 stem 9 projects from the upper end of the valve plug 8. Gas is led to the valve by a pipe line 10 in which is connected a hand valve (not shown) that controls the supply of gas to the entire apparatus.

70 The pilot burner is designated at 12, the particular form shown being that known commercially as the Rutz pilot. This pilot burner includes a combustion chamber 13 having a port in the side thereof adjacent to 75 the main burner 3 through which the flame shoots across the main burner. The flow of gas to this pilot is controlled by a valve 14 which is supplied by a pipe line 15 leading from the main line 10, a hand valve 16 being included in the pipe line 15. Normally 80 the valve 16 is open and the pilot is lighted but only a very small flow of gas is supplied to the pilot since the plunger 17 of the pilot valve 14, Fig. 9, is normally kept 85 closed by a spring 18 and the gas that flows to the burner escapes through the small passage 19. When the main burner is to be turned on, however, a larger flame is desired and a novel mechanism is provided 90 whereby both burners are controlled by a single operating mechanism. For this purpose a vertical rod or shaft 20 is mounted in upper and lower bearings 21 and 22, respectively, Fig. 1, the upper bearing member 95 being secured to the end of the oven 2 and the lower bearing member to one of the frame pieces 23 that supports the oven. A control handle or valve operating handle 24 is secured fast to the upper end of the rod 100 20 and is provided with a pointer 25 which swings over a graduated quadrant 26 formed on the bearing member 21. The arrangement is such, as will be evident from an inspection of Figs. 6 and 7, that the handle 105 24 can swing through an arc of 180° only. Secured to the lower part of this rod is a cam or other eccentric member 28, Figs. 1 and 9, and the peripheral edge of this cam bears against the rounded head of the 110

pilot valve plunger 17. Mounted immediately above this cam 28 and also fast on the rod 20 is a sprocket wheel 29, as shown in Fig. 3, which is connected by a chain 30 to another sprocket wheel 31 secured fast to the stem 9 of the valve plug 8. It is contemplated that the handle 24 can be moved into any one of four principal positions, as shown in Figs. 6 and 7, and it 10 is evident that the extreme range of movement required of the valve plug 8 is 90°, while the rod 20 moves through an angle of 180°. Consequently, the sprocket wheel 29 has half as many teeth as the wheel 31.

15 It will now be clear that when the handle 24 is in its closed or off position, both the valves 7 and 14 will be closed. When it is desired to light the main burner the handle 24 is swung into its full "on" position thus 20 opening both the pilot valve 14 and the main burner valve 7. This results in shooting a strong flame across the top of the main burner thus lighting this burner immediately upon the rush of gas thereinto.

25 I consider it preferable to have the cam 28 so designed that the pilot burner will be opened wide when the main burner valve is at some intermediate point, say its three-quarter position, and that for positions in 30 which the main valve is opened wider or less the pilot valve will be closed, emitting only a small "keep alive" flame. This is for the reason that when the oven is being heated up the main valve usually is wide open and 35 after the temperature of the oven has risen to the desired point, the main valve then is closed to a position about half on. In either of these positions the pilot valve will be closed and thus the waste of gas which 40 would take place if this valve were left open is avoided. At the same time any material danger of explosion is avoided since the movement of the main valve to its wide open position necessarily carries the pilot valve through its wide open position due to the 45 positive connections between the two valves, and the pilot flame would be certain to ignite the gas flowing from the main burner.

A further novel feature of this invention 50 resides in the construction of the main burner, and is best illustrated in Fig. 8. From an inspection of this figure in Fig. 3 it will be seen that the burner nipples 33 are set at angles of approximately 60° with 55 reference to each other and are staggered. This relationship has the advantage of securing a better propagation of the main burner flame than is produced in the usual arrangement. Each of these nipples 60 comprises a head 34, the minimum diameter of which is at its outer end, and the surface of which flares outwardly toward the base. In other words, the head of the nipple is 65 tapered, roughly speaking, but the outer wall is curved inwardly in vertical cross sec-

tion, as is clearly shown in the drawings. This construction, together with the fact that the nipple sets up for a considerable distance above the peripheral surface of the burner pipe 3, is of advantage in producing a very complete combustion of the gases. That is, the gas, as it comes through the mixer 6 becomes mixed with a certain amount of air, but the gas takes up at this point only about one-third of the volume of 70 air required to burn the gas. The other two-thirds must be taken from air surrounding the flame, and this air is commonly referred to as "secondary air." The peculiar nipple construction shown is of advantage 75 in promoting a better circulation of this secondary air and therefore producing a more complete combustion.

This nipple construction also is of advantage from a manufacturing standpoint 85 since the nipples can be made individually by automatic machinery, and the shank 35 is then driven into the hole in the burner pipe 3 until it brings up against the shoulder at the base of the head 34. It is 90 a simple matter to make this driving fit and it produces a tight joint between the burner pipe and the nipple.

A modified construction for effecting the control is shown in Fig. 10. In this arrangement an arm 36 is secured fast to the rod 20 in place of the sprocket 29, and a bell crank lever 37 is secured to the spindle of the valve plug 9 in place of the sprocket wheel 31. A rod 38 connects the arm 36 100 with one arm of the bell crank lever 37, the lengths of the arms 36 and 37 being made such that the spindle 9 is moved 90° upon a movement of 180° of the arm 36. The other arm of the bell crank lever 37 is connected by a link 39 to the sliding sleeve 40 of the Hale mixer.

It will now be seen that this invention provides a very efficient form of burner mechanism which is very economical to 110 manufacture and very convenient to control.

While I have herein shown and described the best embodiment of the invention of which I am at present aware, it will be evident to those skilled in this art that this 115 embodiment may be modified in details of construction without departing from the spirit or scope of this invention.

What is claimed as new is:

1. In a gas heated apparatus, the combination of a main burner, a pilot burner, independent valves controlling the flow of gas to said burners and located adjacent to each other, one of said valves having a reciprocating gas controlling element and 120 the other a rotary gas controlling element, an operating handle, and means connecting said handle with both of said valves for operating them in a predetermined relationship.

2. In a gas heated apparatus, the combination of a main burner, a pilot burner, a rotary valve controlling the flow of gas to said main burner, a plunger valve controlling the flow of gas to said pilot burner, a cam for operating the plunger of the latter valve, and operating mechanism for said valves comprising means positively connecting said rotary valve with said cam whereby said valves are moved in a predetermined relationship to each other.

3. In a gas heated apparatus, the combination of a main burner, a pilot burner, a rotary valve controlling the flow of gas to said main burner, a plunger valve controlling the flow of gas to said pilot burner, a rotary element for operating the plunger of the latter valve, an operating handle, and means positively connecting said handle

with said rotary valve and said rotary element, said means including a sprocket and chain mechanism.

4. In a gas heating apparatus, the combination of a main burner, a pilot burner, a rotary valve controlling the flow of gas to said main burner, a plunger valve controlling the flow of gas to said pilot burner, a cam for operating the plunger of the latter valve, a shaft on which said cam is mounted, an operating handle fast on said shaft, and a positive connection between said shaft and said rotary valve whereby the movement of said handle operates both of said valves in a predetermined relationship to each other.

In testimony whereof I have signed my name to this specification.

NATHAN B. DENISON.
